METHOD AND MEANS FOR REDUCING
ELECTRICAL DISTURBANCES

David G. McCaa, Philadelphia, Pa.

Application January 22, 1930, Serial No. 422,617

18 Claims. (Cl. 250—20)

This invention relates to improvements in methods and means for reducing the effects of electrical disturbances and particularly refers to reducing electrical disturbances in radio receiving systems which may be present in the form of electrostatic discharges from the atmosphere known as "static", or artificial electrical noises. The invention is, of course, applicable to transmission along telephone lines where the disturbances may be in the form of line surges or any other line noises which would tend to predominate over the signaling currents. The general principles of this application are disclosed in co-pending application, Serial No. 74,087, filed 15 Dec. 8, 1925, upon which Patent No. 1,814,051 has been granted. The present invention is in the nature of an improvement on that of the earlier application.

One of the objects of the invention is to provide means which will prevent the transmission of the disturbances to the output of a receiving system, the means depending for operation on the biasing principle, that is, said means being rendered effective by a biasing voltage applied thereto which is of a value comparable with the peak signal voltage.

Another object is to provide means for obtaining the biasing voltage automatically from the receiving system so that it will always be of a value comparable with the peak signal voltage, that is, if the signal voltage increases, the biasing voltage will be automatically adjusted to the required value.

Another object is to provide means in the form of a balanced impedance network or Wheatstone bridge including a variable impedance for rendering the electrical disturbances ineffective on the signal output. The impedance network or Wheatstone bridge is normally unbalanced when no disturbances are present and the signal current is permitted to flow therethrough unaffected. As soon as disturbances of higher voltage are present, the impedance network or Wheatstone bridge becomes automatically less unbalanced to the high amplitude voltages due to variation of value of the variable impedance and, consequently, substantially no voltage due to disturbing voltages, is present in the output of the network.

Another object is to provide a biasing voltage to be applied to the variable impedance device, the value of which depends on the output signals.

Another object is to provide means for preventing the disturbing oscillations from generating biasing voltages.

Another object is the provision of suitable plate voltages for the rectifying tube from which the biasing voltage is derived so that the plate voltage is always of sufficient value to function with the grid bias on the rectifier to give substantially zero plate current when no signals are present. These plate voltages are also provided automatically in accordance with the carrier signal voltage.

A further object is to provide means for automatically biasing the rectifier tube in accordance with the incoming carrier voltage. 10

A still further object of the invention is to provide means for preventing the building up of excessive biasing voltage on the grid of the vacuum tube of a circuit which may be caused by excessively high input voltages and thereby preventing the blocking of the tube. 15

Other objects and advantages will appear hereinafter. 20

The nature and objects of the invention will be better understood from the following detailed description together with the drawings, in which:

Fig. 1 is a basic diagrammatic circuit showing 25 the automatic biasing of a two-element thermionic vacuum tube in accordance with signal voltages;

Fig. 2 is a modification showing two three-element thermionic vacuum tubes which are 30 automatically biased in accordance with signal voltages from the output of a detector tube which may be operated at substantially zero plate current when no signals are present;

Fig. 3 is a wiring diagram of a balanced network or Wheatstone bridge modified in accordance with my invention to prevent electrical disturbances passing therethrough; and 35

Fig. 4 is a wiring diagram of a complete receiving system embodying my improvements and 40 showing the use of the balancing network or Wheatstone bridge and also the connections for obtaining automatic biasing voltages for the tubes in the bridge and for the rectifier from which the bridge bias is obtained. 45

Referring to Fig. 1, V represents a two-element thermionic vacuum tube having an anode *a* and cathode *f* and coupled to the input primary coil *P* by means of secondary *S*. In series with the anode and cathode is inserted a time circuit comprising a resistance *R* shunted by a condenser *C*. A battery *B* with its negative terminal connected through the secondary *S* to the anode *a* is provided to prevent normal 50 55

emission current from flowing from the anode to the cathode of tube V.

The operation of the system shown in this figure is as follows:—When there are no signals present, the tube V is held open or, in other words, the circuit of secondary S is held open-circuited because of the battery B which should be of such a value as to prevent normal emission current from flowing from anode to cathode. By means of the time circuit RC, the tube is held open in accordance with the envelope of the signals, that is, when signals are present, a current begins to flow in the circuit of secondary S and this current produces a voltage drop across the resistance R which causes a more negative voltage to be impressed on the anode, thereby blocking the tube and causing the circuit to become open again. The elements of the time circuit RC are of such value that a predetermined length of time is required for a voltage to build up therein so that signal oscillations which are of a much longer duration than disturbing oscillations render the time circuit effective while the disturbing oscillations such as static surges are of a comparatively short duration cannot build up a voltage therein and, therefore, do not bias the tube.

In Fig. 2 is shown a wiring diagram illustrating the application of the automatic bias voltages produced by the time circuit RC to a system for reducing the effects of electrical disturbances on signal oscillations. The system is of the type described in my co-pending application, Serial No. 383,932, filed Aug. 6, 1929. The automatic bias system of the present invention is substituted for the fixed bias used in the co-pending application. The diagram shows a pair of input terminals 1 and 2 connected to a pair of primary coils P₁ and P₂ which are in series. P₁ and P₂ are inductively coupled in opposed relation to S₃ and independently inductively coupled to secondaries S₁ and S₂, respectively. In the circuit of S₁ are connected in parallel a pair of tubes V and V₁, in the plate circuits of which may be a source of potential B₁. This source of potential is provided to prevent normal emission current from flowing. The grid-filament circuits of the two tubes are connected across the time circuit RC, which is in the anode-cathode circuit of the detector tube V₂. The anode of the detector tube V₂ is energized by the DC source of potential B₂. A filter comprising a suitable choke coil and a condenser C₁ is provided to prevent any sudden surges being impressed on the time circuit RC. The detector in the present instance may be of the type in which the normal plate current is substantially zero. The input for the detector V₂ is provided from the output secondary S₃. The secondary S₂ is connected in series with an adjustable resistance R₂. The resistance R₂ is so adjusted as to balance the impedance of the circuit of the secondary S₁ only when the tubes are conducting. The entire circuit corresponds to a Wheatstone bridge arrangement in which the primaries P₁ and P₂ are analogous to the equal fixed resistances of one arm of the bridge and the circuits of S₁ and S₂ are analogous to the adjustable balancing resistances of the other arm of the bridge. When signals are present in the primaries P₁ and P₂, the circuit of the secondary S₁ is non-conductive because of the bias impressed on the grids of the tubes V and V₁ from the time circuit RC which is obtained by the voltage drop produced by the plate current

from the detector tube V₂. The circuit of the secondary S₂, however, is conductive and the energy from the primary P₂ is diverted thereto, causing an unbalance between the fields of primaries P₁ and P₂, thereby effecting a transfer of signal voltages from the primary P₁ to the secondary S₃. As the strength of the incoming signal oscillations increases or, in other words, as the amplitude increases, the plate current in the detector tube V₂ increases, thereby producing a greater drop across the resistance R and applying a greater negative bias on the tubes V and V₁ to maintain the circuit of the secondary S₁ non-conductive. Thus, it will be seen that the tubes V and V₁ are automatically biased in accordance with the signal amplitude and the circuit of the secondary S₁ is always maintained non-conductive regardless of the value of the peak signal voltage of the incoming oscillations. Undesired oscillations coming in through primaries P₁ and P₂ do not affect the bias on the tubes V and V₁, because the duration of the undesired oscillations is comparatively short and they, therefore, cannot cause the time circuit RC to function since it requires a predetermined length of time to actuate it. As in the case of Fig. 1, the disturbing oscillations such as static surges or line surges lack the time to build up a substantial voltage across the time circuit RC. The peak voltages, however, of the undesired oscillations are sufficiently great to overcome the impedance of the circuit of S₁ and are diverted thereto as well as to the circuit S₂, thereby producing a balance between P₁ and P₂ and preventing any of the undesired oscillations from being transferred to the output secondary S₃.

The operation of the system of Fig. 2 is further enhanced by the fact that the arrangement of the primaries P₁ and P₂ in opposed relation provides a substantially balanced supply for the disturbing oscillations so that their effects are neutralized and cannot be effectively transferred to secondary S₃. However, if there be a slight leakage of the disturbing oscillations to the secondary, they lack the energy and time, as explained hereinbefore, to build up a voltage across RC and, therefore, do not produce a bias on the tubes V₁ and V₂.

In Fig. 3 is shown a balancing network or Wheatstone bridge in which one of the resistances is replaced by a pair of two-element rectifiers which are adjusted by biasing to allow only high amplitude voltages to pass, but to block signal voltages. The bias on these two tubes is provided automatically from the system in which the bridge is located so that when the peak signal voltage increases, a corresponding increase in the biasing voltage will take place. The resistances R₁ and R₂ are fixed and may be equal. The resistance R₃ is variable and may be adjusted so that it will be equal to the total resistance of the tubes V and V₁. Condensers C₃ and C₄ are provided across the resistance R₅ to by-pass alternating current voltages which may leak through from the biasing system and prevent their generating a bias on the tubes V and V₁. The condensers C₃ and C₄ in combination with R₅ also constitute a time circuit which functions to prevent the disturbing voltage such as static surges and the like from over-biasing the tubes. When condensers C₃ and C₄ are not used, alternating current must flow through one-half of the resistance R₅ and the valve in series therewith and the balance point on the adjustable

resistance R_3 shows that the total resistance of valves V_3 and V_4 is (indicated as R_4) effectively high. But when condensers C_3 and C_4 are used in the circuit as indicated, the resistance R_5 balances at a lower impedance value because each condenser presents low impedance to its particular half cycle of alternating current, i. e., C_3 for one-half cycle and C_4 for the other half-cycle, and higher applied voltages cause the valve impedance of V_3 and V_4 to decrease.

The advantages in using C_3 and C_4 may be readily apparent in that all signal oscillations must flow through the resistor R_3 , the lower impedance thereof preventing excessive dissipation of signal energy. Further, the effectiveness of the valves V_3 and V_4 in discriminating between desired oscillations (signals) and undesired oscillations is improved by the use of the condensers C_3 and C_4 .

When the signal voltages are impressed on the input terminals, they are unaffected by the Wheatstone bridge because of the existing unbalance of the bridge and are transmitted to the output terminals through resistances R_2 and R_3 . The reason that the bridge is unbalanced is that the signal voltages cannot pass through the tubes V and V_1 because the tubes are blocked or kept open by the biasing voltage. However, when disturbing voltages, which are of a higher amplitude than the voltage which keeps tubes V and V_1 open, are impressed on the input terminals, the bridge becomes balanced because these voltages render the tubes V and V_1 effective conductors and the resistance represented by R_4 balances the variable resistance R_3 and no current flows to the output. When a combined wave including signals and disturbing voltages is present, there is an output from the bridge to the primary P_4 of transformer T_4 which is substantially proportional to the percentage of signal in the combined wave. Of course, this also holds when there are no disturbing voltages present. This proportion occurs because as the amplitude of the combined wave increases, the bridge becomes more nearly balanced.

In Fig. 4, 1 and 2 represent the input terminals of a receiving system and may be connected to antenna and ground or to any other source of carrier wave signals. The terminals are connected to a primary P_1 of the transformer T_1 which is coupled to the tuned circuit S_1 VC. Radio frequency currents are detected by the tube V_1 and the output of tube V_1 is coupled to the audio frequency amplifier V_2 by means of the transformer T_2 . The output of the tube V_2 is coupled to an intermediate circuit in which is contained the balancing network or Wheatstone bridge arrangement for preventing the disturbing voltages from being transmitted to the push-pull amplifying tubes V_5 and V_6 by means of the transformer T_4 .

The Wheatstone bridge arrangement comprises, as in Fig. 3, the fixed resistances R_1 and R_2 which are equal and comprise one arm of the bridge, the adjustable resistance R_3 and the two-element tubes V_3 and V_4 with a resistance R_5 connected between them which comprise the other arm or balancing arm of the bridge. The resistance R_3 is adjusted to equal the total resistance of the tubes when they are conducting so that the bridge becomes balanced and no current flows to the primary P_4 of transformer T_4 . In practice, the values of R_1 and R_2 are generally of the order of 100,000 ohms each and R_3 is approximately

2000 ohms. The valve resistance of V_3 and V_4 (indicated as R_4) may be approximately 2000 ohms when the valves are conducting and current flows. Therefore, the total load across the secondary S_3 will be less than 4000 ohms when undesired oscillations are present (tubes V_3 and V_4 conducting) but will be approximately 200,000 ohms when signal only is present (V_3 and V_4 not conducting). The secondary S_3 is designed to operate into a load of 200,000 ohms or more and therefore is very inefficient in working into a 4000 ohm load which is the case when undesired oscillations are present and therefore the undesired oscillations will be substantially reduced by this poor and inefficient transfer and thereby enhances the operation of the bridge. The effect, I have chosen to call the "load effect" due to the bridge. A biasing voltage is applied to the tubes V_3 and V_4 through the resistance R_5 which is comparable with the peak signal voltage thereby blocking the tubes for signal voltages and unbalancing the bridge as will be discussed more fully hereinafter. Condensers C_3 and C_4 are provided across resistance R_5 and function as in Fig. 3. The output of the push-pull tubes is coupled to the output terminals 3-4 by means of transformer T_5 . A circuit is coupled in parallel with the output of the tubes V_5 and V_6 containing the primary of transformer T_6 and blocking condensers C_6 . The secondary of this transformer is connected to the grid of a rectifying tube V_7 and to the negative terminal of the time circuit $R'C'$ in the grid-cathode circuit of the tube V_1 . The cathode of the tube V_7 is connected to an intermediate point on the resistance R' . The positive terminal of the time circuit $R'C'$ is connected to the plate of tube V_7 through another time circuit RC . The output of the rectifier V_7 is coupled to a direct current amplifying tube V_8 by means of the time circuit RC . A filter comprising a choke and condenser C_7 is provided to prevent any sudden surges being impressed on the circuit RC . The amplifying tube V_8 is supplied with plate potential from the battery B_2 , and a resistance R_8 is shunted across the anode and cathode of the tube. Plate current from the tube V_8 is caused to flow through the resistance R_8 , producing a voltage drop therein, as indicated by the positive and negative signs, and the negative terminal of the resistance R_8 is connected to one end of the resistance R_5 , while the positive end is connected to the other end of the resistance R_5 through a battery B_1 which provides a zero shunt for the output circuit with no load present, that is, when normal plate current is flowing through the resistance R_8 to produce a voltage drop, an equal voltage is provided by the battery B_1 in the opposite direction, thereby preventing current flow and producing no voltage drop through the resistance R_5 thus preventing bias voltages from being applied to the tubes V_3 and V_4 in the absence of signal. However, when the plate current increases to a value greater than normal, it overcomes the voltage of the battery B_1 , a current flows and a voltage drop is produced in the resistance R_5 corresponding to the increment of plate current.

In shunt with the time circuit $R'C'$ are provided a rectifier D of any suitable half-wave type and a source of uni-directional voltage E in series with the rectifier, and in the present instance, the negative terminal of source E is connected to the input terminal of the rectifier thereby preventing the rectifier from conducting until a positive voltage greater than that of source E is applied to the input terminal.

E is impressed on the rectifier. The positive terminal of E is connected to the positive terminal of R'C'. The voltage of the source E is selected to be equal to the voltage produced across R'C' for the maximum signal for full normal output.

Thus it will be apparent that when the voltage across R'C' is less than or equal to E, the rectifier cannot conduct because of the connection of E in opposition to the conducting direction of rectifier D. However, if a shock voltage or excessively high voltage due to a disturbing carrier at the input terminals 1 and 2 of transformer T₁ is produced across R'C', which is greater than the voltage of E, the rectifier will conduct due to the positive terminal of E being connected to the positive terminal of R'C' and a voltage will be produced across D which is opposite and equal to the difference between the high shock voltage and the maximum voltage of E thereby reducing the voltage across R'C' to the value required for maximum signal for full normal output.

Another feature of the rectifier D and source E when applied to the system of Fig. 4 is that the time constant of the time circuit R'C' is reduced thereby preventing the voltage thereacross from rising above a predetermined value which is the limiting value necessary for the operation of tube V₇, which operation will be explained more fully hereinafter. Hence it will be seen that the effects of shock voltages or of high amplitude voltages of disturbing carriers will be substantially eliminated.

The reduction of the time circuit R'C' for certain voltage ranges may be accomplished in other ways than that shown as for example by reversing elements D and E with respect to each other or with respect to R'C'.

The purpose of the system including the tubes V₇ and V₈ is to provide a bias on tubes V₃ and V₄ across resistance R₅ which will correspond closely to the envelope of the audio frequency signals and to prevent the biasing of tubes V₃ and V₄ when there are no signals or carrier present.

Considering a hypothetical condition in which the tube V₇ may be energized from a constant potential source instead of being energized from the resistance R', as illustrated in Fig. 4 and the source being arranged so that the tube V₇ rectifies energy from the secondary of the transformer T₆, it is obvious that audio frequency signals appearing at the transformer T₄ will be transferred through the tubes V₅ and V₆ and transformer T₆ and will produce uni-directional voltages across resistance R in the plate circuit of the tube V₇ which are substantially proportional to the audio frequency voltages. The voltages developed across the resistance R are amplified by the tube V₈ and appear across the resistance R₈ in the plate circuit of the tube. After being passed through the zero shunt system B₁, R₈, these voltages are applied to the resistance R₅ to bias the tubes V₃ and V₄. Accordingly, the DC voltages across R₅ will correspond to the envelope of the audio frequency signal across transformer T₄.

Therefore, if no provision be made to prevent undesired oscillations from providing a bias across the resistance R₅, they may produce sufficient bias across it to keep the output arm of the bridge unbalanced with respect to the input arm even for the peak voltages of the disturbing oscillations, thereby permitting them to be transferred to the speaker. Using as a basis the fact that the audio frequency signal associated with a given carrier cannot be greater in value than that corresponding to 100%

modulation, resistance R' is provided in the cathode circuit of the signal detector V₁ for supplying energizing voltages for the tube V₇ in accordance with the carrier. The resistance R' provides a D. C. voltage across its terminals, as explained hereinbefore, which is proportional to the carrier voltage only and is unaffected by audio frequency currents. The voltage across the resistance R' is divided by means of a tap, a portion of the voltage being transferred to the grid-filament circuit of the detector tube V₇ to provide a grid bias on the tube and the remaining larger portion being transferred to the plate-filament circuit to provide the necessary plate potential on the tube. The tap on the resistance R' is so adjusted that the normal grid and plate voltages applied to the detector tube V₇ are of a value which best adapts the tube to rectification. From this arrangement, it will be apparent that when no carrier wave is arriving at the detector tube V₁ but only undesired oscillations, such as atmospheric static and the like, in the form of a buzz or other noises, the undesired oscillations will be transferred to transformer T₃ and a certain portion thereof may appear in the output of transformer T₄ which, in turn, will be transferred to the output terminals of the transformer T₆. Obviously, the amount of energy in the plate circuit of the detector tube V₇ is very limited because of the absence of the carrier. Therefore, in the absence of the carrier at the tube V₁, substantially no energy will be transferred from V₇ to V₈ and to resistance R₅ to bias the tubes V₃ and V₄. By reason of this action due to the absence of the carrier, substantially no undesired oscillations will appear at the speaker output terminals. Also, for the same reason, when the carrier is present at the input terminals 1 and 2, but is not modulated, a certain amount of undesired oscillations may leak through the system and pass the valves V₃ and V₄, but the amount of bias is limited by the amount of current flowing through resistance R' in the cathode circuit of the tube V₁, so that the entire system will not respond to severe disturbing oscillations as it might if there were no limit, as is provided by the arrangement of tubes V₇ and V₈.

The beginning of the operation of the bridge in the circuit of Fig. 4 may be better understood from the following:—In the original or normal condition of the complete system, there is no bias on valves V₃ and V₄ and, therefore, the bridge is balanced. Signal oscillations and undesired oscillations alike will be balanced out by the bridge.

The very first cycle of signal oscillations is balanced out in the bridge and does not produce any output in transformer T₄. However, the positive half cycle of the signal flowing through V₃, and through C₃ and the upper portion of R₅ will generate a small negative bias on the plate of V₃. (See Fig. 1 and description thereof.) Similarly, the negative half cycle will generate a small negative bias on the plate of V₄. Valves V₃ and V₄ are now partially biased so that in the next succeeding cycle, a portion of the signal goes to the output transformer T₄ due to the partial unbalance of the bridge by the small negative bias on V₃ and V₄, and provides a normal bias through the biasing system across R₈ of tube V₈, as explained hereinbefore, which builds up slowly and gradually because of time lag in the system due to filters and time circuits until the full strength of signals and bias is produced.

For the first cycle of undesired oscillations such as atmospheric static and the like, the initial

function is the same as for signal oscillations except that by the time the first cycle of the undesired or static oscillations (which are of a damped nature and relatively short duration as compared to signal oscillations) has built up a voltage across R_8 in the output of tube V_8 , the static or undesired oscillation wave train has died out in the bridge and the small over-bias produced by the first cycle becomes ineffective to sustain any bias from R_8 .

If continuous undesired oscillations are present, a limit is provided by circuit $R'C'DE$ where they are in effect short-circuited and prevented from energizing tube V_7 thereby preventing generation of excessive voltages at R_5 and preventing a sustained unbalance of the bridge circuit.

From the above description, together with Fig. 4, it will be apparent that the circuit of my invention provides a system which will automatically prevent undesired oscillations from passing therethrough and prevent their being reproduced in the loud speaker regardless of whether there are signals present or not. It also provides an automatic bias on the tubes in the balancing network or bridge which varies in accordance with the amplitude or strength of the incoming signal voltages to maintain the network or bridge circuit unbalanced with respect to said signal oscillations so that they may be transferred therethrough to the transformer T_4 and through the tubes V_5 and V_6 to the loud speaker terminals and which causes the network to become balanced with respect to the disturbing or undesired oscillations (such as static, line noises, etc.) thereby substantially eliminating any possibility of their being transferred to and through the transformer T_4 and so on to the loud speaker.

The remaining elements of the system which have not been pointed out in detail are elements generally present in any receiving system and function in the usual manner.

The system of Fig. 4 may be susceptible to various modifications. It may be applied to radio frequency systems as well as to the audio frequency system which I have illustrated. The circuits would not be materially different and only the operating values of the essential elements would have to be changed. The circuit including tubes V_7 and V_8 may be omitted and the bias for tubes V_3 and V_4 may be provided directly from the carrier voltage by means of the time circuit $R'C'$ without departing from the principles disclosed. The bias thus derived may be slightly in excess of that required but it would take care of fading of the carrier wave.

While I have shown only two modifications of my invention for the purposes of illustration and description, other changes and modifications therein may be apparent to those skilled in the art without departing from the scope of the invention and I, therefore, desire to be limited only by the scope of the appended claims.

I claim:

1. A system for reducing the effects of disturbing oscillations on signal oscillations comprising an input circuit, an output circuit and an auxiliary circuit associated with said input and output circuits including a pair of thermionic discharge devices normally biased to be rendered non-conductive to said signal oscillations and conductive to said disturbing oscillations thereby causing said signal oscillations to be transferred from the input circuit to the output circuit while the disturbing oscillations are blocked in said auxiliary circuit, and means connected to said output cir-

cuit for deriving a uni-directional voltage which varies in accordance with the amplitudes of the signal oscillations for biasing said discharge devices whereby said devices are always rendered non-conductive to said signal oscillations.

2. A system in accordance with claim 1 in which said voltage deriving means comprises a rectifying device for rectifying a portion of the signal oscillations and an impedance network coupling the output of the rectifying device to the input of said pair of thermionic discharge devices.

3. A system in accordance with claim 1 in which said voltage deriving means comprises a rectifying device for rectifying a portion of the signal currents and a time circuit comprising a resistance and capacity in parallel connected between the output of the rectifying device and the input of said pair of thermionic discharge devices whereby the current from the rectifying device produces said biasing voltage which is applied to said discharge devices, and a filter in the output of said rectifying device for preventing sudden surges of current being applied to said time circuit.

4. In a receiving system, means for reducing the effects of disturbing oscillations on signal oscillations comprising a normally unbalanced Wheatstone bridge connected between the input and output circuits of said system to pass said signal oscillations therethrough, one arm of said bridge comprising a fixed resistance and another resistance and another arm comprising a second fixed resistance equal to said first fixed resistance and a pair of thermionic discharge devices normally rendered non-conductive to signal oscillations, but conductive to the disturbing oscillations, the combined resistance of said devices, when conducting, being balanced by said other resistance to balance the bridge, whereby the disturbing oscillations are rendered ineffective on said output circuit, and means for maintaining said discharge devices non-conductive to said signal oscillations in accordance with the amplitudes of said signal oscillations.

5. In a carrier wave receiving system, means for reducing the effects of disturbing oscillations on signal oscillations, comprising a balancing impedance network into which both of said oscillations pass, means for deriving a uni-directional voltage from the system which varies in accordance with the envelope of the signal oscillations, means for deriving a second voltage from the system which varies in accordance with the carrier, means for causing said second derived voltage to limit the first derived voltage to a predetermined extent, and means for applying the limited voltage to said impedance network whereby said network is unbalanced for the signal oscillations to permit them to pass therethrough.

6. In a carrier wave receiving system comprising a stage of carrier frequency amplification, a detector stage, and a stage of audio frequency amplification, means for reducing the effects of disturbing oscillations on signal oscillations comprising a normally unbalanced impedance network between the input and output of said system whereby said signal oscillations may pass through said network, means for rectifying a portion of said signal oscillations whereby a uni-directional voltage is produced, means for deriving a plurality of uni-directional voltages from the carrier wave for energizing said rectifying means in accordance with the carrier to limit the voltage from said rectifying means, and means

for applying said limited voltage to said network, whereby said network is maintained balanced for the disturbing oscillations and unbalanced for the signal oscillations.

- 5 7. In a receiving system, means for reducing the effects of disturbing oscillations on signal oscillations comprising a balancing network including a plurality of unilateral impedance devices, a time circuit associated with said unilateral impedance devices whereby a biasing voltage is built up to render said unilateral impedance devices non-conductive for said signal oscillations thereby causing said network to become unbalanced to pass said signal oscillations therethrough, means 10 15 for deriving a uni-directional voltage from said signal oscillations and means for applying said derived voltage to said network to maintain said unbalance, and means connected between said balancing network and said last-mentioned 20 25 means for preventing sudden surges of voltage affecting said network.

8. In a receiving system, means for reducing the effects of disturbing oscillations on signal oscillations comprising a balancing impedance network including a plurality of unilateral impedance devices, a time circuit associated with said unilateral impedance devices comprising a resistance connected between said unilateral devices and a pair of condensers, each of which is connected to a portion of said resistance whereby a biasing voltage is built up to render said devices non-conductive for said signal oscillations thereby causing said network to become unbalanced to pass said signal oscillations therethrough, means for deriving a uni-directional voltage from said signal oscillations, and means for applying said derived voltage to said network to maintain said network unbalanced for said signal oscillations.

- 40 9. In a receiving system, means for reducing the effects of disturbing oscillations on signal oscillations comprising a balancing network, normally unbalanced to cause said signal oscillations to pass therethrough, means for amplifying said signal oscillations from the output of said network, means for deriving a uni-directional voltage from said amplified signal oscillations, and means for applying said derived voltage to said network whereby said network is maintained unbalanced for said signal oscillations in accordance with their amplitudes.

- 55 10. In a radio receiving system, a vacuum tube having a grid and a cathode, a time circuit comprising a condenser shunted by a resistor interposed in series between said grid and said cathode, and means for preventing the building up of an excess charge on said time circuit due to excessively high voltages which may be impressed on the input of said system, said means comprising an asymmetrical device provided with a suitable biasing voltage and connected in shunt with said time circuit.

- 60 11. In a receiving system, means for reducing the effects of disturbing oscillations on signal oscillations comprising a balancing impedance network including a plurality of uni-lateral impedance devices, and a time circuit associated with said uni-lateral impedance devices comprising a resistance connected between said uni-lateral devices and a pair of condensers, each of which is connected to a portion of said resistance whereby a biasing voltage is built up to render said devices non-conductive for said signal oscillations thereby causing said network to be-

come unbalanced to pass said signal oscillations therethrough.

12. In a receiving system, a balancing device comprising a thermionic discharge device, said thermionic device being normally unbiased to effect a balance of said balancing device, means for deriving a biasing potential for said thermionic device from the output of said balancing device to unbalance the same for currents of predetermined amplitude, and means for causing the initial cycle of said currents to set up a biasing potential on said thermionic device to unbalance said balancing device and initiate operation of said first mentioned means.

13. In a receiving system, a balancing device comprising a pair of thermionic discharge devices, said thermionic devices being normally unbiased to effect a balance of said balancing device, means for deriving a biasing potential for said thermionic devices from the output of said balancing device to unbalance the same for currents of predetermined amplitude, and means for causing the initial cycle of said currents to set up a biasing potential on said thermionic devices to unbalance said balancing device and initiate operation of said first mentioned means.

14. In an electrical wave signaling system, a signal transfer stage comprising a Wheatstone bridge including a pair of thermionic discharge devices in one arm thereof, means for supplying incoming signals to said signal transfer stage, means for deriving a unidirectional voltage from selected incoming signals having a desired amplitude, said voltage varying in accordance with the amplitudes of said selected signals, and means for applying said unidirectional voltage to said discharge devices in such direction that the transfer effectiveness of said signal transfer stage increases as said selected signal increases.

15. In an electrical wave signaling system, a signal transfer stage comprising a Wheatstone bridge including a pair of thermionic discharge devices having a resistance connected between them in one arm of said bridge, means for supplying incoming signals to said signal transfer stage, means for deriving a unidirectional current from selected incoming signals having a desired amplitude, said current varying in accordance with the amplitudes of said selected signals, means for passing said current through said resistance to produce a unidirectional voltage, and means for applying said unidirectional voltage to said discharge devices in such direction that the transfer effectiveness of said signal transfer stage increases as said selected signal increases.

60 16. In an electrical wave receiving system, means for receiving waves of different frequencies, a transfer stage for waves of certain frequencies, means for controlling the transfer effectiveness of said stage, means for deriving control energy from said waves of certain frequencies and for applying said energy to said control means, and for deriving control energy from waves of another frequency and for applying said energy to said control means, whereby the transfer effectiveness of said transfer stage is controlled in accordance with the amplitude of said waves.

65 70 17. In a modulated carrier wave receiving system, a demodulator, a transfer stage for the signal waves produced by demodulation, means for controlling the transfer effectiveness of said stage, means for deriving control energy from said signal waves and for applying said energy to said

control means, and means for deriving control energy from the carrier wave and for applying said energy to said control means, whereby the transfer effectiveness of said transfer stage is controlled in accordance with the amplitude of said waves.

18. In a modulated carrier wave receiving system, a demodulator, a transfer stage for the signal waves produced by demodulation, means for controlling the transfer effectiveness of said

stage, means for deriving unidirectional control energy from said signal waves and for applying said energy to said control means, and means for deriving unidirectional control energy from the carrier wave and for applying said energy to said control means, whereby the transfer effectiveness of said transfer stage is controlled in accordance with the amplitude of said waves. 5
